UNITED STATES PATENT OFFICE.

WILLIAM H. NELSON, OF HAZLETON, IOWA.

SASH-FASTENER.

1,138,396.

Specification of Letters Patent.

Patented May 4, 1915.

Application filed May 23, 1914. Serial No. 840,510.

To all whom it may concern:

Be it known that I, WILLIAM H. NELSON, a citizen of the United States of America, and a resident of Hazleton, Iowa, have invented 5 certain new and useful Improvements in Sash-Fasteners, of which the following is a specification.

My invention relates to improvements in sash-fasteners, and the object of my invention is, first, to furnish fastening means for upper and lower sashes of a window-frame, adapted to permit of the adjustment and holding in a desired position of either sash relative to said window-frame; second, to 10 arrange the parts of said fastening-means so that they will be inaccessible to any one operating from the outside of the window, thus making it virtually a burglar-proof fastening.

20 These objects I have accomplished by the means which are hereinafter fully described and claimed, and which are illustrated in the accompanying drawings, in which:

Figure 1 is a horizontal section through 25 adjacent parts of two window-sashes, with the abutting jamb of the window casing showing my improved fastening-means seated in said casing in a position to lock the said sash in certain positions, parts of said 30 structures being broken away. Fig. 2 is an elevation of said window-jamb, said sashes and my improved sash-fastener, with the cover removed from the casing of the latter. Fig. 3 is an upper plan view of the sash- 35 fastener casing alone, with the contents removed. Fig. 4 is an upper plan view of said casing, showing the movable spring-controlled bolts seated therein, with the parts which ordinarily are superposed thereon removed. Fig. 5 is a perspective view of the 40 said sash-fastener casing, with the sliding closure in place. Fig. 6 is a perspective view of one of the sliding bolts of said device. Fig. 7 is a perspective view of the 45 sliding keeper for the two sliding bolts. Fig. 8 is a perspective view of one of the flat springs. Fig. 9 is a perspective view of the detachable securing means for the shifting-bolt.

50 Similar numerals of reference denote corresponding parts throughout the several views.

My said invention is an improvement upon my sash-fastener, which was patented to me 55 by the United States, July 22, 1902, under No. 705,282.

My improved sash-fastener comprises an oblong casing 1, open at the top, a slide cover 2 to close said casing. The bottom of said casing is divided by a relatively low 60 medial longitudinal partition or ridge 6, end to end, integrally, and on opposite sides of said ridge and somewhat staggered with relation to each other are the rectangular openings 3 and 4 in the bottom of the casing of 65 sufficient length to permit the bolts 8 and 27 of the slides 7 to project therethrough, and permit the free movement therealong.

The slides 7 and 15 are seated in oblong parallel seats on opposite sides of said ridge 70 6, and said slides have on their diminished ends 10 and 16, respectively, parallel springs 12 and 17 mounted thereon, with the other ends of said springs bearing against the adjacent end walls of said casing. Said slides 75 have projections 9 and 14, respectively, projecting oppositely from the bolts 8 and 27.

The numeral 16^a represents a slide-body which is of an oblong shape, with staggered recesses 17^a and 21 on its opposite longitudinal sides, and having at its ends the parts 80 18 and 22 bent over at right angles upwardly, and provided with notches 20 and 23, respectively, near one side of each, but located oppositely relative to each other and to 85 the body part 16. The end projection 18 has a threaded aperture 19 adapted to receive the threaded end of a screw 30, the latter having an enlarged portion beginning at the shoulder 29 and terminating with a finger-piece 90 or head 28.

The slide-body 16^a is placed within the casing 1 so that its opposite recesses 21 are located to receive the projections 9 and 14, respectively, on the slides 7 and 15. The 95 numerals 24 and 39 denote similar flat springs, each having an aperture 26 near one end, and each being provided with a projecting part 25 or 40, extending to one side thereof. These springs are seated within 100 the casing, as indicated, in Fig. 2, where the spring 24 is secured by a rivet passed through its aperture 26 to the casing, the other end of the spring being seated movably in the groove 20 in the end 18 of the 105 slide-body 16^a. The spring 39 has a similar attachment to the opposite wall of the casing at the opposite end of the latter and its free end is movably seated in the slot 23 in the projection 22. In these positions, the 110 projections 25 and 40 on said spring, extend into the paths of movement of the projec-

tions 9 and 14 of the slides 7 and 15, and prevent said projections ordinarily passing them when being moved toward them.

Referring now to Figs. 1 and 2, the numeral 34 denotes one of the jamb or side parts of a window-casing, having the upper and lower window-sash 35 and 36 seated in proper movable relation thereto, said sashes having on their inner vertical angles of the side stiles the squared sockets 37 and 38, respectively, which are ordinarily vertically staggered with relation to each other. These sockets are in line with the bolts 8 and 27, respectively, when said bolts are, as shown in Fig. 1, seated in said sockets and held there by the yieldable resilient pressure of the springs 12 and 17.

The jamb 34 has a cavity 41 in its part, which projects into a room, and said jamb is also recessed to permit the passage of the screw 30 through said jamb and chamber 41, as shown. The shoulder 29 of said screw is adapted to engage the inner wall of the cavity 41 to form a stop for the screw.

Referring now to Fig. 9, the numeral 31 denotes an escutcheon centrally orificed to receive said screw 30 slidably. The escutcheon has, in its upper part, a channel part 32, open at the top and bottom, and whose channel is adapted to receive a slide bolt 33 having its upper end bent over to form the finger-piece. The lower end of said bolt, when in its lowered position, is adapted to be received below said raised part 32 into a transverse groove or notch 34 on the screw 30. By the use of this bolt 33, the screw 30 may be prevented from turning and prevented from being pulled in or out. Since the screw 30 is detachably secured to the bent-over end of the slide-body 16, it is evident that when the screw is pushed in, the bolt 27 is pushed out from the sash 36 to clear and permit the raising or lowering of said sash to a desired distance, the bolts being housed in the notch in the guide strip. When the screw 30, by means of its finger-piece 28, is pulled out, the opposite bolt 8 is released from the sash 35, and the other sash becomes locked by the releasing of the bolt 27 and its being moved back into its socket 38 by means of the spring 17.

When the screw 30 is detached from the slide-body 16, the fastener has both its bolts 8 and 27 retracted into the sockets 37 and 38, respectively, by the action thereon of the springs 12 and 17. The bolts cannot be displaced from these locked positions with the sashes except by the use of some means from the inside of the room for shifting the slide-body 16 to and fro, which would not be practical without the use of a similar screw 30. The fastener, therefore, is practically a burglar-proof one, and cannot be released from the sashes by the use of any ordinary means. It will be noticed that the bolts 8

and 27 cannot be displaced from the recesses 37 and 38, respectively, by slipping a thin piece of steel, such as a knife blade, between the sash and the jamb and against either. This is due to the fact that the projections 9 and 14, respectively, are stopped by the projecting parts 25 and 40 on the flat springs 24 and 29, respectively, which prevents the withdrawal of the bolts. However, when the slide-body 16 is moved in either direction by the use of the finger-piece 28 connected thereto, one or the other spring is acted upon by the means of the projection 18 or 22 in sliding thereover to push said spring inwardly, thereby withdrawing inwardly the projections 25 or 40, respectively, and out of the path of movement of the projections 9 or 14 ordinarily stopped thereby. The continued movement of the slide-body in the same direction will then push over the projection 9 or 40 enough to release the bolt which is integral therewith from the desired sash to be unfastened. It is obvious that a different form of stop from those shown at 25 and 40 may be used, or that the spring device 24 and 39 may be otherwise formed and arranged, without deviating from the principle of my invention. However, to avoid the removal of the screw 30 at frequent intervals, the locking bolt 33 is provided, whereby said screw may be held against movement, and which would not be easily manipulated by anyone without the window.

Having described my invention, what I claim as new, and desire to secure by Letters Patent, is:

1. A sash-fastener, consisting of the combination of window-sashes having recesses in the side stile thereof having bolts arranged to engage the sides of said recesses, a slide-piece recessed to actuate said bolts, springs to hold said bolts in engagement with said recesses in the sashes, a key adapted for detachable connection with the said slide-piece, stops movably interposed in the paths of movement of said bolts, and operative connections between said stops and said slide-piece adapted to separately shift either stop when the slide-piece is moved by said key in an appropriate direction.

2. A sash-fastener, consisting of the combination of window-sashes having recesses in the side stile thereof having bolts arranged to engage the sides of said recesses, a slide-piece recessed to actuate said bolts, springs to hold said bolts in engagement with said recesses in the sashes, a transversely notched key adapted for detachable connection with the said slide-piece, stops movably interposed in the paths of movement of said bolts, and operative connections between said stops and said slide-piece adapted to separately shift either stop when the slide-piece is moved by said key in an appropriate direction.

tion, and means for detachably locking said key against movement, comprising a fixed support, and a bolt slidably mounted thereon and adapted to releasably engage the 5 notch in said key.

3. A sash-fastener, consisting of the combination of window-sashes having recesses in the side stile thereof having bolts arranged to engage the sides of said recesses, a slide-piece recessed to actuate said bolts, springs 10 to hold said bolts in engagement with said recesses in the sashes, a key adapted for detachable connection with said slide-piece, springs, each secured at one end and having 15 its other end slidably connected to said slide-piece, each spring having a stop-projection ordinarily projected into the path of movement of the adjacent bolt, the said slide-piece when moved to and fro, acting to 20 shift either of the latter springs to remove its stop-projection from the path of movement of the adjacent bolt.

4. A sash-fastener, consisting of the combination of a window-sash having recesses in 25 the side stile thereof having a bolt arranged to engage the sides of said recesses, a slide-piece recessed to actuate said bolt, a spring to hold said bolt in engagement with said recesses in the sash, a key adapted for detachable connection with the said slide- 30

piece, a stop movably interposed in the path of movement of said bolt, and a flat spring on which said stop is mounted and having one end fixed and the other end slidably connected to said slide-body. 35

5. A sash-fastener, consisting of the combination of a window-sash having recesses in the side stile thereof having a bolt arranged to engage the sides of said recesses, a slide-piece recessed to actuate said bolt, a spring 40 to hold said bolt in engagement with said recesses in the sash, said slide-piece having on one end an upwardly-bent part provided with a slideway in its upper edge, a flat spring having one end fixed with its other 45 end seated slidably in the said groove, a stop on said flat spring projected into the path of movement of said bolt to prevent the shifting thereof from a recess of said sash, and means detachably connected to said 50 slide-piece adapted to move it to cause it to slidably compress said flat spring to move the stop thereon out of the path of movement of said bolt.

Signed at Waterloo, Iowa, this 7th day of 55 May, 1914.
